L. G. RATTERMAN

HOLDER FOR NEWSPAPERS, MENUS, AND THE LIKE

Filed June 4, 1925

FIG. 1.

FIG. 2.

FIG. 4.

FIG. 3.

INVENTOR:
Louis G. Ratterman
BY David C. Carlsen
ATTORNEY.

UNITED STATES PATENT OFFICE.

LOUIS G. RATTERMAN, OF ST. PAUL, MINNESOTA.

HOLDER FOR NEWSPAPERS, MENUS, AND THE LIKE.

Application filed June 4, 1925. Serial No. 34,862.

My invention relates to a holding device particularly useful on dining room tables either in the home, restaurants, hotels, club rooms and other places. The object is to provide a simple, inexpensive and useful device for holding newspapers, menus and other reading matter in a convenient position in front of a person partaking of a meal.

In the accompanying drawing:

10 Fig. 1 is a perspective view of my device in operative position.

Fig. 2 is a top view and Fig. 3 a side view of my device alone in a form consisting of two sections hinged together.

15 Fig. 4 is a front perspective of a modified form of my device.

Referring to the drawing by reference letters, my device is preferably made entirely of wire and comprises a horizontal part 20 and an upright part, the latter constituting the holding device. The horizontal part is simply a wire loop A from which extends in a common plane two parallel arms B. Said arms B are bent upwardly at a 25 predetermined distance from the loop A, as at C, forming two upright arms D preferably in a common plane and inclined toward each other, thence bent downwardly and centrally as E to two horizontally spaced 30 bends F adapted to normally contact with the surface S on which the loop A rests. Thence the wire is extended upwardly to form an upright central finger G closed and terminating as at H. The upright part of 35 my device may thus be considered as comprising three upwardly directed fingers (see Fig. 4) all made of a single piece of wire and integral with the parallel arms B.

In Figs. 1 and 4 the entire device is made 40 of a single piece of wire there being, in Fig. 1, an opening in the loop A between the arms B and the wire of said loop A is made forming also the arms B and the holder members just described. In all forms 45 of the device a common dinner plate or other similar tableware J is placed so as to rest on loop A or engage it in such a way as to hold it down. Before meal times, in restaurants and like places, a menu (not shown) 50 may be placed in the holder and on other occasions when a person wishes to read a newspaper K or other printed matter while eating he simply places the paper or other

reading matter in the stand by slipping it downwardly in front of the two upright 55 fingers D—E with the central finger G engaging the front surface of the paper (see Fig. 1) the three arms being sprung according to the thickness of the paper inserted and frictionally holding it so that a person 60 eating food off of plate J may read the paper while eating.

In Figs. 2 and 3 two pieces of wire are used in making the device, A being a complete wire loop and having two spaced integral eyelets A' adapted to be hingedly engaged by similar eyelets B' on the forward ends of the arms B. The latter arms (B) and the upright finger members are made of a single piece of wire and may be folded over 70 the loop A, as indicated in dotted lines in Fig. 3, when not in use or for shipping purposes.

In Fig. 4 the entire device comprises a single piece of wire, the loop A beginning 75 with an eyelet A'' thence bent in a circle and the wire passed through said eyelet thence straight back as to C' and upwardly and downwardly to form the three arms described and then forwardly from C'' to the 80 loop A about which the other end of the wire is looped at B''. It will be readily seen that in all cases the upright wire fingers form a rack which acts as a paper clip, on a large scale, to frictionally engage and 85 hold a newspaper, menu, price tag or any other reading matter.

It is obvious that in either the rigid or folding type of my device the wire may be bent and assembled in various ways and in 90 the case of using a complete loop as A in Fig. 2 the wire ends may be spot welded, soldered or otherwise made integral as at M in Figs. 1 and 2.

What I claim is:

1. In a holder of the class described, a skeleton frame comprising a flat section of approximately circular form and adapted to lie on a horizontal surface and be retained thereon, an upright section connected with 100 said flat section and in spaced relation thereto horizontally and comprising in part a number of upwardly directed fingers adapted to frictionally retain flat objects in upright position and in spaced relation to the flat section, and pivots connecting said two 105

sections to make the upright section foldable upon the flat section.

2. The structure specified in claim 1 in which a part of said upright section comprises two parallel arms, the main part of the flat section comprising a wire loop adapted to lie on a table and be retained thereon by an article of tableware.

3. The structure specified in claim 1 in

which a part of said upright section comprises two parallel arms, the main part of the flat section comprising a wire loop adapted to lie on a table and be retained thereon by an article of tableware, said two parallel arms and the wire loop adapted to be normally disposed in a common plane.

In testimony whereof I affix my signature.

LOUIS G. RATTERMANN.
